FIG.15

FIG.16

FIG.17

FIG.18

FIG.19

FIG.20

FIG. 1 is a front elevation of an article of flatware showing my new design as embodied in a fork;

FIG. 2 is a side view of the fork;

FIG. 3 is a rear view of the fork;

FIG. 4 is a top view of the fork;

FIG. 5 is a bottom view of the fork;

FIG. 6 is a front elevation of an article of flatware showing my new design as embodied in a teaspoon;

FIG. 7 is a side view of the teaspoon;

FIG. 8 is a rear view of the teaspoon;

FIG. 9 is a top view of the teaspoon;

FIG. 10 is a bottom view of the teaspoon;

FIG. 11 is a front elevation of an article of flatware showing my new design as embodied in a salad fork;

FIG. 12 is a side view of the salad fork;

FIG. 13 is a rear view of the salad fork;

FIG. 14 is a top view of the salad fork;

FIG. 15 is a bottom view of the salad fork;

FIG. 16 is a front elevation of an article of flatware showing my new design as embodied in a knife;

FIG. 17 is a side view of the knife;

FIG. 18 is a rear view of the knife;

FIG. 19 is a top view of the knife; and

FIG. 20 is a bottom view of the knife.

The distinguishing feature of my new design for an article of flatware resides in the handle configuration.

I claim:

The ornamental design for an article of flatware, as shown and described.
